TREATMENT OF HYDROCARBON OILS

Jacque C. Morrell and Gustav Egloff, Chicago,
Ill., assignors to Universal Oil Products Com-
pany, Chicago, Ill., a corporation of South
Dakota

No Drawing. Application January 30, 1931
Serial No. 512,477

1 Claim. (Cl. 196—36)

This invention relates to the treatment of hydrocarbon oils, and refers more particularly to the refining of the relatively low boiling hydrocarbon distillates.

5 In one of its specific aspects the invention embodies a process for the refining of cracked hydrocarbon oils and comprises subjecting such oils to treatment with sulphur trioxide and steam in the presence of iron oxide.

10 The invention has especial application to the refining of the lighter hydrocarbon distillates in the vapor phase and is particularly useful in the refining in the vapor phase of the relatively low boiling products resulting from the conversion of 15 hydrocarbon oils by subjecting the said vapors from the cracking process during or subsequent to fractionation to treatment with sulphur trioxide and steam in the presence of iron oxide.

The usual method of refining cracked distillates is to subject them to treatment with sulphuric acid and alkaline solutions, including plumbite solutions consisting of litharge dissolved in alkaline solutions in various combinations of treatment and subsequently to subject 25 the acid treated product to redistillation usually in the presence of steam. The present invention permits the direct treatment of the hydrocarbon vapors from the cracking process, reducing the cost of reagents and eliminating the redistillation 30 or rerunning operation, although it is within the scope of the invention to revaporize the product in a subsequent operation and subject the vapors to treatment as described.

In applying the process of the invention to practice any suitable equipment may be employed 35 which will permit the contacting of the hydrocarbon vapors and the sulphur trioxide and steam with the iron oxide; for example, a suitable tower or chamber packed with the oxide may be 40 employed following the fractionator of a cracking system, feeding the sulphur trioxide and steam directly to the tower, thus permitting contact of the hydrocarbons to be treated with the iron oxide and sulphur trioxide from any suitable 45 source, alone or in combination with steam, which may be introduced directly into the tower or treating vessel containing the iron oxide. In lieu of direct packing of the tower or treating vessel with the iron oxide an inert filling material 50 such as Raschig rings, firebrick, crushed rock, gravel, crushed ceramic material, and the like, suitably coated with iron oxide, may be employed. Similarly, any device which permits the efficient 55 contacting of the vapors undergoing treatment with the iron oxide may be employed.

The tower or treating vessel containing the iron oxide may be directly connected to a cracking unit or to a rerun or redistillation unit so that the vapors arising therefrom may be treated in the manner described.

60 It has been found desirable to neutralize the distillate immediately after condensation either by passing the condensate directly through a body of alkaline material such as a solution of caustic soda or by washing the distillate free 65 of excess sulphur trioxide or sulphur dioxide resulting from the treatment with water and/or alkalies, such as a solution of caustic soda, ammonia or the like. The neutralizing agent may also be introduced into the vapor line leading 70 to the condenser or into the condenser itself.

The amount of sulphur trioxide employed may vary from a fraction of a pound to several pounds, based on a barrel of hydrocarbon distillate.

75 Sulphur trioxide itself alone or preferably with steam may be employed. Various temperatures of treatment may be employed, for example, from 250—600° F., more or less, and the pressures may be sub-atmospheric, atmospheric, or superatmospheric. While the results may vary with the 80 temperatures employed, the pressures and temperatures are chosen so that the hydrocarbons are treated substantially in the vapor phase.

In order to reduce the intensity of the reaction the sulphur trioxide may be admixed with 85 an inert gas such as flue gas, carbon dioxide and the like, and is preferably introduced at various points in the treating tower.

90 As specific examples of the operation of the process of my invention and of the results obtained, a California cracked distillate of approximately motor fuel boiling range is vaporized and subjected to treatment with sulphur trioxide and steam in the presence of iron oxide. The vapors are passed at a suitable rate through 95 the tower containing the iron oxide and approximately one pound per barrel of sulphur trioxide is introduced into the tower. The untreated product shows a gum content of approximately 400 mgs. per 100 ccs. and was a reddish brown 100 color. The sulphur content was approximately 0.20. The treated product shows a gum content of approximately 20 mgs. per 100 ccs. and has a color of plus 25 on the Saybolt colorimeter scale. The sulphur content is reduced to approximately 105 0.18. The gum determinations are made by the copper dish method.

110 When the iron oxide is distributed over pumice stone similar results to those just described were obtained.

A mixed Mid-Continent and West Texas cracked distillate when treated in the vapor phase with sulphur trioxide and steam employing iron oxide as a contacting agent gives the following results: The untreated distillate shows a gum content of approximately 350 mgs. per 100 ccs. and a light amber color. The treated distillate may be reduced in gum content to approximately 20 mgs. per 100 ccs. and a color of approximately 10 25 on the Saybolt colorimeter scale. The sulphur content may be reduced also.

With a Mid-Continent distillate containing approximately 350 mgs. of gum per 100 ccs. and having a dark yellow color one may obtain a 15 product containing approximately 30 mgs. of gum per 100 ccs. having a color of approximately 25 on the Saybolt colorimeter scale and with an appreciable reduction in sulphur content by 20 treatment with sulphur trioxide and steam employing approximately one-half of a pound of sulphur trioxide per barrel, based on the distillate treated.

Distillates containing several hundred mgs. of 25 gum per 100 ccs., more or less, and of a dark color, from various sources such as those from West Texas, California, Mid-Continent, Pennsylvania, and the like, may be treated in the presence of iron oxide with approximately one-half to several pounds of sulphur trioxide in the pres- 30

ence of some steam, to produce marketable products of low gum content, good color, odor and stability.

The above examples are only illustrative and should not be construed as restrictions or limitations on the broad scope of the invention. 80

The treatment herein described may constitute the sole refining action on the oil, or it may constitute one step in a series of refining steps. It may be preceded by the usual treatments with refining agents such as sulphuric acid, caustic soda, plumbite, filtering earth or the like, and may be succeeded by any combination of the above refining agents, followed, if desired, by distillation. 85

We claim as our invention:

A step in refining the overhead gasoline-containing product resulting from the cracking of hydrocarbon oil, which comprises subjecting said product in heated vaporous condition to treatment with sulphur trioxide and steam in the presence of an iron oxide under conditions capable of removing sulphur and gum and color forming constituents from the product without destruction of the major portion of the gasoline 100 hydrocarbons contained therein. 95
